UNITED STATES PATENT OFFICE.

ROBERT E. HUMPHREYS, OF WHITING, INDIANA, ASSIGNOR TO STANDARD OIL COMPANY, OF WHITING, INDIANA, A CORPORATION OF INDIANA.

CANDLE-DIPPING MACHINE.

Application filed June 14, 1923. Serial No. 645,303.

To all whom it may concern:

Be it known that I, ROBERT E. HUMPHREYS, a citizen of the United States, residing at Whiting, in the county of Lake and State of Indiana, have invented new and useful Improvements in Candle-Dipping Machines, of which the following is a specification.

The present invention relates to improvements in candle dipping machines and will be fully understood from the following description thereof, illustrated by the accompanying drawings, in which—

Figure 1 is a side elevation, partly broken away of a machine embodying the present invention,

Fig. 2 is a plan view of a portion of the track and of the carrier for the candle supports,

Fig. 3 is a vertical sectional view on the line 3—3 of Fig. 1,

Fig. 4 is a side elevation, partly broken away, of a candle support,

Fig. 5 is a plan view, partly broken away, of a candle support,

Fig. 6 is an enlarged detailed view in side elevation of a portion of a candle support, showing the mode of engaging a candle thereby, and

Fig. 7 is a vertical sectional view on the line 7—7 of Fig. 6.

The machine of the present invention is for the purpose of dipping candles, either wholly or partly pre-formed, for the purpose of completing their formation or, more generally, for applying a superficial coating of colored wax thereto. Referring more particularly to the drawings, the numeral 10 indicates a steam bath in which is provided a container or tub 11 for melted wax, in general colored by means of a dye or pigment. On each side of the dipping tank 11 are provided spaced parallel rails 12 and 13, the rails 12 being adjacent the tank. Wheeled frames 14 are mounted on each set of rails 12 and 13, these frames being provided at their tops with spaced angle irons 15 which serve as tracks for the movement of the carriers for the candle supports. The frames 14 are connected by substantially U-shaped frame members 16 (illustrated as formed of separable members bolted together), these frame members straddling the tub 11. Centrally from the upper transverse portion of each of the U-

shaped members 16 arises a vertical post or bar 17. Upon the posts 17 is slidably mounted a dipping frame 18, the latter being provided with projecting bored members 19 through the openings of which the bars 17 pass.

The dipping frames 18 are formed of parallel angle irons 20 secured to bail members 21 and held in their proper relative positions by transverse braces 22. The angle irons 20 of the dipping frame are the same distance apart as the angle irons or tracks 15 of the frames 14 and, when the dipping frame is in position such that the angle irons 20 are on the same level as the angle irons or tracks 15, continuous tracks for the movement of the carriers for the candle supports are provided as shown, for example, in Fig. 2.

The carrier for the candle supports, 75 shown most clearly in Figs. 2 and 3, is suitably formed of two depending U-shaped members 23 held in spaced parallel relation by bars 24 and mounted upon the rollers or wheels 25. This wheeled carrier, upon which the supports for the candles may be placed, can be moved along the tracks or angle irons 15 to the dipping frames 21, where it may be brought to rest and caused to move vertically downward with the latter.

The vertical movement of the dipping frame is effected in the following manner. To the bail members 21 of the dipping frame is secured a strap or belt 26, which passes over pulleys 27 and 28 mounted on a supporting frame 29 which in turn may be conveniently mounted upon the U-shaped supporting frames 16 previously referred to. The strap 26 then passes downwardly over a small pulley 29^a mounted on a shaft 30 which is provided at its end with a gear 31 meshing with a second gear 32 mounted on a parallel shaft 33 driven by a hand wheel 34. The shafts 30 and 33 are likewise mounted in suitable bearings provided on the frame 29. From the pulley 29^a the strap 26 passes over a pulley 35, then over a pulley 36 mounted on standards 37 supported on the frame 29 and at the end of the strap is secured a counter-weight 38, which counterbalances the dipping frame when loaded with a candle support carrier and the candle supports.

The supports for the candles are shown in 110

detail in Figs. 4, 5, 6 and 7. As illustrated, these candle supports are formed of an inner angle iron 40 and an outer angle iron 41 nested together and longitudinally movable relative to each other. They may be secured together, for example, by rivets 42 fixed in the outer angle irons 41 and passing through slots 43 in the inner angle irons 40. A number of such fastenings are provided in each web of the angle irons forming the candle supports. In corresponding webs of the angle irons 40 and 41 there are provided slots or openings 44 and 45 respectively from the edge inward, these openings being aligned when the angle irons 40 and 41 are directly superposed over each other. By longitudinal movement of the inner angle iron 40, these openings are caused to overlap until an edge of each slot 44 in the inner angle iron 40 meets or passes the opposite edge of the openings 45 in the lower angle iron 41, thereby pinching and holding the wick 46 of a candle 47 which has previously been placed in the slot. This longitudinal movement of the inner angle iron with respect to the outer one may readily be effected by the device shown in detail in Figs. 6 and 7. An L-shaped opening 48 is provided in the inner angle iron 40, through which extends a pivot pin 49 secured, by riveting or otherwise, in the outer angle iron 41. Within the angle a bell crank lever 50 is mounted on this pivot pin, the shorter arm of this bell crank lever being provided with a pin 51 which enters one arm of the L-shaped opening 48. On movement of the bell crank lever 50, the pin 51 engaging the sides of one arm of the opening 48 in the inner angle iron 40 causes movement of the latter thereby pinching or releasing the wicks of candles inserted in the slots 44 and 45.

In operation the entire device, by movement of the tracks 12 and 13, is brought into position over a selected dipping pot 11. By manipulating the hand wheel 34, the dipping frame is brought to its normal raised position, the angle irons 21 forming the track of the dipping frame being then aligned with the tracks 15. A number of the candle supports having previously been filled by pinching the wicks of candles therein in the manner already described, a suitable number of these candle supports are laid longitudinally of a carrier, resting on the cross-bars 23 with the candles depending as shown in Fig. 3. When one

of the carriers has been loaded it is rolled along the tracks 15 on one side of the dipping frame until it rests on the tracks 21 of the dipping frame itself. By manipulation of the hand wheel 34 the dipping frame is then moved downwardly until the candles enter the melted wax in the dipping pot and after a proper length of immersion, they are raised therefrom. When the dipping frame has returned to its normal raised position, the carrier with its load of dipped candles is rolled onto the tracks 15 opposite those on which it was loaded. In the meantime other carriers have been similarly loaded and as soon as the load of dipped candles is removed from the dipping frame, a carrier loaded with candles to be dipped is rolled upon it, the dipping operation being then repeated.

Although the present invention has been described in connection with certain specific details of apparatus embodying the same, it is not intended that these details shall be regarded as limitations upon the scope of the invention, except in so far as included in the accompanying claims.

I claim:

1. In a candle dipping device, a candle support comprising superimposed plates having corresponding slots opening from the edge inward and means for retaining said plates in juxtaposition while permitting longitudinal movement of one with respect to the other.

2. In a candle dipping device, a candle support comprising nested angle irons, corresponding openings formed in one of the webs of each of said angle irons, said openings being formed from the edge inward, and means for retaining said angle irons in juxtaposition while permitting longitudinal movement of one with respect to the other.

3. In a candle dipping device, a candle support comprising a pair of nested angle irons, said angle irons having corresponding slots formed in one of the webs of each of them, said slots opening from the edges inwardly, means for retaining said angle irons in juxtaposition while permitting longitudinal movement of one with respect to the other, a pin secured to one of said angle irons and means mounted upon said pivot pin and engaging the other angle iron for causing longitudinal movement thereof.

ROBERT E. HUMPHREYS.
